CLAIM

The ornamental design for a vehicle battery cover, as shown and described.

DESCRIPTION

FIG. 1 is a front elevational view of the vehicle battery cover of the present invention;

FIG. 2 is a back elevational view of the vehicle battery cover of FIG. 1;

FIG. 3 is a left side elevational view of the vehicle battery cover of FIG. 1;

FIG. 4 is a right side elevational view of the vehicle battery cover of FIG. 1;

FIG. 5 is a bottom plan view of the vehicle battery cover of FIG. 1;

FIG. 6 is a top plan view of the vehicle battery cover of FIG. 1; and,

FIG. 7 is a top, front right side perspective view of the vehicle battery cover of FIG. 1 in use.

The broken lines showing a battery in FIG. 7 are for illustrative purposes only and form no part of the claimed design.

The broken lines shown in the rectangular strips of FIG. 1, 2 and 7 are indicative of backstitching.
